ware

Application May 4, 1951, Serial No. 224,540

9 Claims. (Cl. 260—679)

This invention relates to a process and apparatus for the production of acetylene and more particularly to a process and apparatus for the production of acetylene from hydrocarbons such as methane. In the past it has been proposed to produce acetylene by processes involving the subjection of hydrocarbons such as methane to very high temperature conditions for short periods of time. Such previously employed processes include those in which an electric arc is used to supply the necessary heat for the conversion as well as those processes in which methane is heated in externally fired tubes or is passed intermittently over hot refractory materials. However, these processes have not been entirely satisfactory because of the expense involved, low conversion rates and inability to produce a truly continuous process.

This invention has for an object the provision of a continuous process for preparing acetylene from hydrocarbons such as methane in which a portion of the heat necessary for the reaction is supplied by the partial combustion of the hydrocarbon itself.

A further object of this invention is the provision of a readily controllable process in which a hydrocarbon, such as methane, and oxygen are mixed in the relatively cool condition and then preheated to an elevated temperature prior to the time that they are subjected to a partial combustion reaction.

A still further object of this invention is the provision of a process that may be readily controlled to insure that the partial combustion and concomitant production of acetylene occurs in the reactor and not elsewhere in the equipment.

A still further object of this invention is the provision of a process which is carried out in such a manner that a mixture of a hydrocarbon, such as methane, and oxygen may be heated to elevated temperatures before passing to the acetylene-producing reaction section.

A still further object of this invention is the provision of a process and apparatus for heating a mixed stream of oxygen and a hydrocarbon, such as methane, to an elevated temperature without substantial reaction.

A still further object of this invention is the provision of a method of initiating a combustion reaction in a reaction chamber in which acetylene is produced from a hydrocarbon.

A still further object of this invention is the provision of a process and apparatus for preparing acetylene from natural gas.

Further and additional objects will appear from the following description, the accompanying drawings and the appended claims.

In accordance with one embodiment of this invention, a hydrogen gas, such as methane, is mixed in a relatively cool condition with oxygen. The cool mixture is then passed at a high linear velocity through a tubular coil furnace whereby the stream is heated to a temperature between about 1200° and 2000° F., the linear velocity of the stream being maintained such that combustion of the methane will not occur within the tubular heater.

2

Thereafter the preheated mixture is passed through an unobstructed enlarged reactor in which partial combustion of the methane is allowed to occur. This partial combustion results in the consumption of substantially all of the oxygen and simultaneously raises the heat of the reaction mixture to a temperature between about 2000° and about 3000° F., thereby converting the unburned methane to acetylene. The gases undergoing combustion are passed through the reactor at a high linear velocity so that the temperature reached during combustion is only maintained for a very short period, i. e. between about 0.001 and about 0.01 second. Thereafter the hot reacted gases containing substantial amounts of acetylene are quenched and subjected to an acetylene recovery process. As will be more clearly pointed out hereafter, the conditions of the process may be controlled so that the quenched exit gases from the reactor contain in excess of 10 percent by volume of acetylene.

Another aspect of this invention resides in the method and means for preheating a high velocity stream of oxygen and a hydrocarbon under conditions to heat it to a temperature between 1200° and 2000° F. under conditions substantially preventing any reaction between the oxygen and methane therein at the prevailing temperatures. In accordance with one embodiment of this invention, this object is achieved by providing a pre-heater furnace having a pair of fire chambers separated by two closely spaced refractory walls. A tubular heating coil for the hydrocarbon-oxygen mixture is placed between the two refractory walls and the latter are heated by suitable burners directing flames against the opposite outside surfaces thereof. Thus the tubular heating coil between the refractory walls is heated solely by radiant heat, thereby insuring even heating substantially throughout the entire length of the coil.

For a more complete understanding of this invention, reference will now be made to the accompanying drawings, wherein

Fig. 1 is a flow plan showing in diagrammatic form an apparatus for carrying out the process of this invention;

Fig. 2 is a broken perspective view showing a pre-heater furnace constructed in accordance with one embodiment of this invention;

Fig. 3 is a vertical sectional view of the preheater furnace shown in Fig. 2 taken along the line 3—3 thereof;

Fig. 4 is a top plan view of the preheater furnace shown in Fig. 2 with a portion being shown in section taken along the line 4—4 of Fig. 3; and

Fig. 5 is a sectional view of one embodiment of a reactor or combustion chamber which may be employed for carrying out the process of this invention and also illustrating means for quenching the hot reaction products.

In carrying out the process of this invention, it is preferred to employ natural gas as the source of methane for the production of the acetylene. Ordinarily dry natural gas may contain about 95% methane and about 5% of ethane and heavier hydrocarbons. Preferably all of the hydrocarbons heavier than methane are removed from the natural gas charged. To this end and with reference to Fig. 1, natural gas (suitably containing 95% methane and 5% higher hydrocarbons) is introduced to the apparatus through line 10 into pump 12 wherein it is compressed to between 900 and 1000 pounds per square inch whereafter it is passed through line 14 into the lower portion of a conventional absorber 16. Absorber oil, such as kerosene, is passed into the top of the absorber 16 through line 18 and is withdrawn from the absorber through line 20. At the elevated pressure obtaining within the absorber (e. g. 900 to 1000 p. s. i. g.) substantially all of the hydrocarbons heavier than methane are absorbed by the oil and substantially pure methane

is withdrawn overhead from the absorber 16 through line 22. The enriched oil withdrawn through line 20 may be cycled to any suitable recovery process for the separation of the absorbed gases and recycled to the absorber. The methane stream in line 22 usually containing in excess of 99% methane is then passed through a reducing valve 23 wherein the pressure is reduced to about 200 p. s. i. g. and then through a knock-out drum 25 and a charcoal adsorber 24 in order to remove any small amounts of absorber oil that may have been carried over. Thereafter the substantially pure methane is passed through line 26 and a flow control valve 28 whereby the pressure of the methane is reduced to about 100 pounds per square inch or less in line 30.

Charcoal adsorption has been specifically referred to as a method for removing absorber oil from the methane stream. However, a mechanical separator may be employed for this purpose. Also a charcoal adsorber or refrigerating system may be substituted for the oil absorber system if desired to separate heavier than methane gases. It is preferred in actual practice to separate hydrocarbons heavier than methane from the charge gas since such hydrocarbons tend to induce the oxidation reaction at a much lower temperature than when the methane content is 99% or higher and such an oxidation reaction is not desired in the coils of the preheater furnace later to be described. It will also be appreciated that the methane charged to the system may contain small amounts of inert impurities, such as nitrogen and carbon dioxide, without appreciably affecting the process.

When the process of this invention is in operation, oxygen is admixed with the methane in a relatively cool state. This oxygen from any suitable source is introduced at a usually obtaining high pressure through line 36, a flow control valve 42 and line 44 into a suitable mixing box 46 at about 100 pounds per square inch pressure or less. Under preferred conditions of operation, substantially pure oxygen is passed to line 36. However, under certain conditions air may be employed as the source of oxygen if suitable compensation is made in hereinafter described reaction concentrations, time of reaction and other factors that will be apparent to one skilled in the art.

In normal operations the amount of oxygen that is mixed with the methane in the mixing box 46 is less than the amount that would be required for the complete combustion of the methane. In actual practice it has been found to be satisfactory to employ a volume ratio of oxygen to methane of about 1 to 2. The mixing box 46 may be of any desired structure which will permit the oxygen and methane streams from the lines 44 and 30 to become thoroughly mixed in the relatively cool condition. After mixing, the cool stream is then passed through line 50 to a coil 52 of a preheater furnace. This preheater furnace preferably has the structure indicated in more detail in Figs. 2, 3 and 4 hereinafter to be described. The tubular coil 52 itself is preferably formed of a high chrome steel alloy which is capable of being heated to temperatures up to about 2000° F. or higher without deterioration. Allegheny Metal 28—Stainless Steel AISI Type No. 446 has been found to be particularly satisfactory. Steels containing high percentages of nickel are usually to be avoided. The pressure of the gases passing through the preheater coil is dependent upon flow rates, tube size, temperature of the gases in the tube, flow resistance due to friction, etc. and this pressure is adjusted so that the gaseous mixture passes through the coil 52 at an extremely high velocity, the gaseous pressure at the outlet end of the coil being only slightly in excess of atmospheric, e. g. $\frac{1}{2}$ pound per square inch gauge.

If desired, a section of the preheater coil may be bypassed by a portion of the cool charge mixture through line 54, valve 56 and line 58 which latter discharges into the coil 52 at juncture 59. This by-pass provides an ef-

fective means for controlling the temperature of the preheated gases discharged from the preheater coil 52 through line 61.

The reactor, as most clearly shown in Fig. 5, comprises an enlarged elongated tube 64 which is formed of a highly refractory material such as silicon carbide. Such a material is suitably "Carbofrax" or "Refrax" obtainable from The Carborundum Company. However, any inert material capable of withstanding temperatures in excess of about 3000° F. may be employed. In the form of the device shown in the drawing, this reactor tube has an inner diameter of about 2 inches and is about 23 $\frac{1}{2}$ inches long. The reactor tube is closed at its forward end by means of a plate 66 of a refractory or other suitable material which is apertured to receive the discharge line 62 from the preheater and to receive a thermowell 68. The thermowell may contain a plurality of thermocouple elements (not shown) which are employed for measuring the temperature within the tube 64 at a plurality of positions, such as T₁, T₂ and T₃, shown in Fig. 5.

The main body portion of the reactor tube 64 is encased within a box suitably lined with insulating refractory bricks 71 (see Fig. 5), such as Type G-26, and an outer layer of insulation 73, such as "Hi-temp." The box may also be enclosed within a steel casing, if desired (not shown in Fig. 5). A plurality of horizontally arranged silicon carbide electrical resistance elements 70 are positioned within the reactor box in spaced relationship to the reactor tube 64. These elements (known to the trade as Globars) may be initially heated to temperatures in excess of about 3000° F. whereby the temperature of the reactor tube 64 is elevated to a neighborhood of about 2000° F. or higher. However, when the reaction is under way, the temperature of the elements 70 may be cut down, as hereinafter more fully described, to provide a condition in which the temperature within the reaction section of the reactor tube 64 is several hundred degrees higher than the temperature within the box outside of the reactor tube.

During operation the mixture of methane and oxygen preheated in coil 52 is introduced at an extremely high velocity through the tube 62 into the reactor 64. Due to the fact that the reactor 64 has a larger cross section, the linear velocity of the gaseous mixture is somewhat reduced but nevertheless this mixture passes at a high velocity through the reactor itself. The gaseous mixture is allowed to undergo a partial combustion within the reactor tube 64. At the beginning of the process this partial combustion may be initiated by controlling the intensity of the heat applied by the electrical resistance elements 70. However, after the reaction once gets under way and the combustion produces substantial quantities of heat, then the heat supplied by the resistance elements 70 may be cut down or diminished to a substantial extent. The heating elements 70 serve to supply the heat necessary to initiate the combustion reaction and, during operation, serve only to overcome the heat loss attendant to the use of temperatures in the range of 2000° to 3000° F. in the reactor. The partial combustion of the gases in the reaction chamber 64 may be controlled so that the actual combustion or burning reaction occurs in the rearward end of the tube, that is, the end of the tube remote from the end plate 66. Thus in a typical operation the combustion within the reactor 64 is controlled by adjusting the preheat temperature so that the temperature of the acetylene-producing reaction (above about 2000° F.) is not achieved in the gases until after the gases have passed points T₁ or T₂ in the reaction chamber 64. The velocity of the gases is so great in the reactor that the combustion temperature in excess of about 2000° F. is maintained only for a period less than about 0.01 second before it has been discharged from the rearward end of the tube 64. The combustion reaction consumes the oxygen to liberate the necessary amount of heat required for the conversion of unburned methane into acetylene. The com-

burntion mixture is then quenched at once upon discharge from the reactor 64 by means of a converging water spray supplied through a perforated circular ring 72. The temperature of the gases is thereby immediately reduced to prevent undesirable side reactions, such as excessive carbon formation and/or the polymerization of the acetylene. Thereafter the quenched reaction gases are further cooled by passing into a quench tank 74 and upwardly through a tower 76 into the top of which cooling water is introduced through line 78. The tower 76 suitably contains Raschig rings to provide an effective cooling area and water is circulated to a cooling tower (not shown) through a line 80 extending from a lower portion of the quench tank. The quenched reaction gases withdrawn from the tower 76 through line 82 contain essentially hydrogen, carbon monoxide, carbon dioxide, unreacted methane and acetylene. In order to recover the acetylene, these gases are pumped by pump 84 under pressure through line 86 and the heat exchanger 88 and a line 90 to an acetylene absorber 92. The acetylene absorber liquid may comprise acetone, acetaldehyde, acetonitrile, nitrobenzene, chlorinated hydrocarbons, polyglycols and their esters, or any of those that are known in the art for absorbing acetylene from gases of this character. The enriched absorber liquid is discharged from absorber 92 through line 94 to a suitable acetylene recovery apparatus (not shown). Tail gases from which substantially all of the acetylene has been removed are withdrawn overhead through line 96 and regenerated absorber liquid is passed to the absorber through a line 98.

An important feature of this invention is the provision of a particular type of furnace preheater for the methane-oxygen mixture. It will be borne in mind that it is preferred, in accordance with the process of this invention as above described, to preheat the oxygen-methane mixture to a temperature between about 1200° F. and about 2000° F. without initiating a combustion reaction. This can be done by employing a preheater furnace of the character disclosed in Figs. 2, 3 and 4. This furnace comprises essentially a pair of firing chambers 100 and 102 laterally spaced from each other and separated by a pair of spaced refractory walls 104 and 106 between which is defined a narrow radiant heating chamber 108. The walls 104 and 106 are constructed of a highly refractive material such as silicon carbide which will withstand direct firing at temperatures in excess of 3500° F. and which have an extremely high heat transfer rate. The forward end wall 110 which is common to the firing chambers 100 and 102 is provided with two vertically spaced rows of apertures 112 through which extend gas pipes or burners 114 connected to a main gas supply 116. These burners impinge against offset bricks 118, thereby directing flames in a horizontal direction along the opposing sides of the refractory walls 104 and 106. Products of combustion escape from the chimneys 120 and 122. Thus it will be apparent that the flames do not impinge directly against the preheater coil 52 and local overheating which may cause burning within the tube is thereby avoided. Also oxygen of the air does not circulate through the radiant heating chamber in contact with the coil 52. It will be noted from Fig. 4 that the discharge line 62 is wrapped with insulation 124 to prevent heat loss between the preheater and the reactor 64. This insulation material is not indicated in the drawing of Fig. 1.

It will be apparent from the foregoing description of the apparatus that much equipment not shown in the drawing will be employed in actual commercial practice of this invention. Thus the drawings do not show various meters, valves, heat exchangers and recording instruments, the use of which is well known to those skilled in the art and is contemplated within the scope of this invention.

For a more complete understanding of this invention, reference will now be made to a specific example showing the manner in which the process of this invention

may be carried out. It will be appreciated, however, that this example is not to be construed as limiting the broad aspects of the invention herein claimed. Streams of oxygen and methane were mixed in the mixing box 46 without preheating and at ambient temperature (i. e. about 82° F.). The methane was fed to the mixing box at the rate of 2,481 standard cubic feet per hour and the oxygen was fed at the rate of 1,301 standard cubic feet per hour. Thus the volume ratio of oxygen to methane was approximately 1 to 2. This relatively cool mixture was then passed into the line 50 at about 34 pounds per square inch gauge, this pressure being sufficient to force the mixture at an extremely high linear velocity through the preheater coil 52. The preheater coil in this example comprised a 20 foot length of $\frac{3}{4}$ inch chrome steel alloy tubing in a fore part of the furnace (up to juncture 59) secured to an 11.7 foot section of $\frac{7}{8}$ inch chrome steel tubing beyond juncture 59. The coil was serpentine in shape as shown in Fig. 5 and constituted five passes between the hot refractory walls 104 and 106. These walls were spaced about $2\frac{1}{2}$ inches apart forming a narrow radiant heating chamber about $6\frac{1}{2}$ feet long and $3\frac{1}{2}$ feet high. The furnace temperature was adjusted and a small amount of charge gas (24 standard cubic feet per hour) was by-passed through valve 56 so that the outlet temperature of the furnace was controlled to 1750° F. At this temperature substantially no reaction between the methane and oxygen occurred in the furnace, this being at least in part due to the extremely high velocity of the gases forced therethrough, the pressure of the gases at the discharge end of the preheater being substantially atmospheric. Under these conditions the velocity of the gas entering the preheating furnace was about 142.5 linear feet per second and the velocity of the gas at the outlet end of the preheating furnace was about 1480 linear feet per second. The gaseous mixture heated under these conditions was then passed, as above described, directly into a 2 inch silicon carbide (Carbofrax) reactor tube which was about $23\frac{1}{2}$ inches long and which contained a thermowell with thermocouples, as indicated in Fig. 5. The No. 2 thermocouple (T₂) was positioned 8 inches from the discharge end of the reactor tube 64. The silicon carbide electrical resistance elements 70 were heated to a sufficient temperature to permit partial combustion to be maintained within the reactor tube, the gas velocity from the discharge end of the reactor tube being about 348 feet per second.

Under the conditions indicated, the combustion occurred in the tube 64 essentially downstream of the point T₁ (see Fig. 5), the temperature at this point being about 1900° F. The temperature at point T₂ was 2150° F. and the temperature at point T₃ was 2700° F. (point T₃ being about 3 inches from the discharge end of the tube). The average residence time of the individual gas molecules in the reactor 64 was about 0.00813 second while the reaction time (residence time between T₂ and the quench) was about 0.00219 second. The combustion gases were immediately quenched with the converging water spray as above described and the acetylene was recovered from the reaction gases through an acetone absorption system. The reaction gases discharged to the quench tower had the following analysis in volume per cent (dry basis):

Acetylene	11.3
CO ₂	2.0
Unsaturates	0.2
Oxygen	0.5
CO	20.2
Hydrogen	58.1
Methane	7.7
	100.0

The above indicated analysis indicates a yield of acetylene amounting to 216 standard cubic feet per hour on

the basis of 1000 standard cubic feet per hour of methane fed to the process. This is the equivalent of 14.8 pounds of acetylene per 1000 standard cubic feet per hour of methane fed to the system.

From the foregoing it is clear that a simple and readily controllable process has been provided for preparing acetylene from methane. A particular feature of the invention involves the step of mixing the methane and oxygen while in the relatively cool state and thereafter preheating them together to obtain a desired pre-combustion temperature. It has been in the past proposed to preheat either the methane or the oxygen before mixing. However, where this has been done, the process has been extremely difficult to control and almost always the combustion will eventually occur directly at the mixing point, resulting in inefficient conversion and rapid disintegration of the mixing nozzles. A further feature of the invention is the passing of the mixture of hydrocarbon gas and oxygen through the preheater at an extremely high velocity, thus reducing the time factor and permitting a high heat transfer rate in order to prevent undesired combustion from occurring directly within the preheater. If combustion is allowed to occur at this point, extremely high temperatures will be generated which will serve to burn out the coils in short order. On the other hand, it is desired that the preheating be carried out in a manner to achieve as high a temperature as possible before introducing the preheated stream into the reaction zone. The higher the preheat, the less oxygen is required in the mixture to supply the autogenous heating necessary for the acetylene-forming reaction. Likewise, less methane is consumed in the combustion reaction leaving more gas for acetylene production. A contributing factor in permitting this high heat to be achieved without substantial reaction in the preheater is the construction of the preheater furnace itself as previously described. In the modification of the preheater employed in the specific example given above, the silicon carbide refractory walls were spaced about 2½ inches apart and the serpentine coil was spaced therebetween by means of ordinary refractory brick.

In starting up the process, the preheater is first fired and the electrical resistance elements of the reactor are turned on. Pure methane gas with or without small quantities of oxygen is then passed through the preheater coil and the reactor until such time as the effluent from the preheater is in excess of about 1200° F. and until the temperature at point T₂ in the reactor has reached about 2100° F. The addition of small amounts of oxygen during the start-up and during the eventual cooling down periods seems to increase the life of the heating coils. Thereafter additional oxygen is slowly introduced into the system through line 36 until the optimum concentration has been reached at the mixing box 46. As the oxygen is introduced, combustion starts in the reactor to produce the desired temperatures. It is important not to allow the temperature in the reactor to exceed about 3000° F. since the higher temperatures will result in the formation of an undue amount of carbon together with substantial polymerization of acetylene. After the desired reaction temperature has been obtained, the resistance elements 70 may be cut out of the system or the heat liberated therefrom reduced so that the desired temperature may be maintained.

In the form of the reactor shown in Fig. 5, it was found that during operation carbon had a tendency to collect on the surface of the heating elements 70 perhaps due to hydrocarbon gases diffusing into the chamber surrounding the reaction tube 64. This difficulty was eliminated by continuously introducing a small stream of nitrogen or other inert gas into the chamber. Other means than the electrical resistance elements 70 may be used to impart external heat to the reactor 64, however, electrical resistance heating is one of the few methods capable of reaching sufficiently high temperatures nec-

sary to overcome heat loss in the apparatus shown when operating in the range of 2500° to 3000° F.

As indicated in the foregoing, it is preferable that the exit gases from the preheater have a temperature between about 1200° and 2000° F. and a feature of this invention resides in the discovery that under controlled conditions a mixture of methane and oxygen may be heated to these high temperatures without reacting.

Best results have been achieved, however, where the preheat temperature is between about 1600° and 1900° F. Likewise, as suggested above, the combustion temperature should be between about 2000° and 3000° F. Apparently the acetylene reaction begins just at about 2000° F. but carbon formation begins to take over at the temperatures above 3000° F. Temperatures that have been found most suitable for the reactor are within the range of 2600° to 2950° F.

If desired, an initiator or promoter, such as propane, acetaldehyde, acetone or the like, may be added in small quantities directly to the reactor tube 64 through line 60 (see Fig. 1) whereby to assist in controlling the combustion therein.

In order to avoid polymerization of the acetylene that is formed, it is preferred that the pressure within the reactor be at about atmospheric pressure or even less. Likewise exceedingly short reaction times are important, preferably less than 0.01 of a second, suitably between 0.01 and 0.001 second, longer times being permissible where lower temperatures are employed.

As pointed out in the foregoing, this invention finds primary application in the production of acetylene from natural gas and particularly from methane. Usually it is preferred to employ substantially pure methane in order that the operations may be stabilized. The presence of other higher hydrocarbons will have a tendency to initiate a combustion reaction in the preheater coil which is undesirable. Also for this reason, the adsorber 24 is employed to prevent higher hydrocarbon materials (e. g. absorber oil vapors) from getting into the preheater coil. On the other hand, after the methane-oxygen stream has been preheated to the optimum amount, it may be desirable under certain conditions to add an initiator, such as acetaldehyde or acetone or a higher hydrocarbon (ethane, propane, etc.), in order to assist the combustion in the reactor 64. Such an initiator is useful in starting the combustion reaction and maintaining it in the reactor. Such an initiator may be added, as suggested above, by means of line 60 directly into the reactor 64 through a suitable opening (not shown) in the end plate 66.

In large scale commercial operations the use of the resistance elements 70 or other heating means may be dispensed with entirely after the reaction has been started since, where heat losses are not too rapid, the appropriate temperatures may be maintained by the partial combustion in the reactor. It is, of course, readily apparent that heating means, other than electrical resistance elements, may be employed when necessary for the reactor tube 64.

It will also be understood that the process of this invention, in its broader aspects, is applicable to other hydrocarbon gases, such as ethane or propane. However, if such gases are used, either alone or in admixture with methane, lower preheat temperatures than those suggested above may be necessary.

While particular embodiments of this invention are suggested above, it will be understood, of course, that the invention is not to be limited thereto, since many modifications may be made, and it is contemplated, therefore, by the appended claims, to cover any such modifications as fall within the true spirit and scope of this invention.

I claim:

1. A process of producing acetylene from a normally gaseous hydrocarbon which comprises mixing gaseous

streams of oxygen and said hydrocarbon, the amount of oxygen in the resulting mixture being less than that required for the complete combustion of the hydrocarbon, heating the resulting mixture in a first elongated confined stream to a temperature between about 1600° and about 1900° F., said stream moving at a high linear velocity under conditions to prevent substantial combustion of the hydrocarbon therein, then passing the heated stream through an enlarged reaction zone at a high linear velocity less than the linear velocity of said first stream and in the absence of a substantial amount of free hydrogen separately passed into said zone, partially combusting said mixture in said reaction zone at a temperature in excess of about 2000° F., the average residence time of the molecules undergoing reaction at said last-mentioned temperature being less than about 0.01 second whereby substantial quantities of acetylene are produced, immediately quenching the reacted mixture after said residence time, and separating acetylene from the quenched reaction mixture.

2. A process of producing acetylene from methane which comprises mixing relatively cool gaseous streams of oxygen and methane, the amount of oxygen in the resulting mixture being less than that required for the complete combustion of the methane, passing the resulting cool mixture through an elongated heating coil at a high linear velocity under conditions to prevent substantial combustion of methane therein, heating said mixture in said coil to a temperature between about 1600° and about 1900° F., maintaining the linear velocity of said mixture through said coil at a value sufficient to prevent said substantial combustion of methane, then passing the heated stream through an enlarged reaction zone at a high linear velocity less than the linear velocity of the stream discharged from said coil and in the absence of a substantial amount of free hydrogen separately passed into said zone, partially combusting said mixture in said reaction zone at a temperature in excess of about 2000° F., the average residence time of the molecules undergoing reaction at said last mentioned temperature being less than about 0.01 second whereby substantial quantities of acetylene are produced, immediately quenching the reacted mixture after said reaction time has elapsed, and separating acetylene from the quenched reaction mixture.

3. A process of producing acetylene involving the partial combustion of methane which comprises mixing relatively cool streams of oxygen and substantially pure methane, thereafter introducing the mixture at high linear velocity into an elongated externally heated coil, heating the stream in the coil and simultaneously controlling the linear velocity of the stream therethrough whereby the temperature of the stream is raised to between about 1600° and 1900° F. and no substantial reaction between the oxygen and the methane is allowed to occur therein, thereafter passing the thus heated stream into an enlarged reaction zone in the absence of a substantial amount of free hydrogen separately passed into said zone, effecting a partial combustion of the mixture in said zone at a temperature between about 2000° and about 3000° F., maintaining the average residence time of the molecules at said reaction temperature for a period of between about 0.001 and 0.01 second whereby substantial quantities of acetylene are formed, immediately quenching the partially combusted mixture after said residence time, and separating acetylene from the quenched mixture.

4. A process of producing acetylene from natural gas containing methane and higher hydrocarbons which comprises separating substantially pure methane from said higher hydrocarbons, mixing in a relatively cool state a stream of said methane with a stream of oxygen, the amount of oxygen being less than that required to effect a complete combustion of the methane, passing the combined stream through an elongated coil preheater at a high velocity to prevent a combustion reaction within the

coil, discharging the substantially unreacted gaseous stream from said coil into an enlarged reaction zone at a temperature between about 1600° and about 1900° F. and in the absence of a substantial amount of free hydrogen separately passed into said zone, partially combusting the heated gases in said reaction zone whereby elevated temperatures between about 2000° and about 3000° F. are attained, maintaining said gases at said elevated temperatures in said reaction zone for a period of between about 0.001 and about 0.01 second, thereafter quenching the reacted gases, and separating the acetylene produced therefrom.

5. A process of producing acetylene from methane which comprises passing a relatively cool stream comprising a mixture of a major proportion by volume of methane and a minor proportion by volume of oxygen through an elongated radiantly heated tubular coil whereby the mixture is heated to a temperature between about 1600° and about 1900° F., said stream having a sufficiently high linear velocity in said coil to prevent substantial reaction of the oxygen with the methane therein, discharging said heated stream into an enlarged refractory tubular reaction zone through which said gases also pass at a high linear velocity and in the absence of a substantial amount of free hydrogen separately passed into said zone, maintaining combustion of said mixture within said reaction zone whereby the temperature of the gaseous mixture is raised to between about 2600° and about 2950° F., maintaining said last mentioned temperature for a short period of time not exceeding about 0.01 second, thereafter quenching the hot reaction gases, and separating therefrom the acetylene thus produced.

6. A process for the production of acetylene from methane which comprises passing a stream of a mixture of methane and oxygen through an elongated tubular coil positioned between a pair of closely spaced refractory walls, firing opposite outside surfaces of said walls whereby said coil is heated externally from opposite sides solely by radiant heat, said stream being heated in said coil to a temperature between about 1600° and about 1900° F., flowing said stream through said coil at a high linear velocity sufficient to prevent substantial reaction between the oxygen and the methane within the coil at said temperature, and then passing said stream through an enlarged reaction zone in the absence of a substantial amount of free hydrogen separately passed into said zone to effect partial combustion of methane and conversion to acetylene.

7. In a process for the production of acetylene by the partial combustion of methane, the steps of passing a mixture of methane and oxygen at a high linear velocity through an elongated tubular coil, heating said tubular coil under high rate of heat transfer conditions solely by radiant heat whereby localized heating of said coil with attendant tendency to develop hot spots therein is substantially prevented, discharging the heated mixture in the substantially unreacted state from said coil at a temperature between about 1600° and about 1900° F. to a reaction zone, and combusting said mixture in said zone in the absence of a substantial amount of free hydrogen separately passed into said zone at a temperature between about 2000° and about 3000° F.

8. A process of producing acetylene involving the partial combustion of methane which comprises mixing relatively cool streams of oxygen and substantially pure methane, thereafter passing the mixture through an elongated externally heated coil, heating the mixture in said coil to a temperature of the order of 1750° F. while maintaining the linear velocity of said mixture through said coil sufficiently high to prevent substantial reaction between said oxygen and said methane within said coil, thereafter discharging the thus heated mixture at a linear velocity of the order of 1480 feet per second into an enlarged reaction zone and in the absence of a substantial amount of free hydrogen separately passed into said

zone, effecting a partial combustion of the mixture in said zone at a temperature between about 2600° and about 2950° F., maintaining the average residence time of the molecules at said reaction temperature for a period of time less than about 0.01 second whereby substantial quantities of acetylene are formed, immediately quenching the partially combusted mixture after said residence time, and separating acetylene from the quenched mixture.

9. A process of producing acetylene from a normally gaseous hydrocarbon comprising essentially methane which comprises mixing relatively cool gaseous streams of oxygen and said hydrocarbon, the amount of oxygen in the resulting mixture being less than that required for the complete combustion of the hydrocarbon, passing the resulting relatively cool mixture into an elongated heating coil, heating the mixture in said coil by means of externally applied heat to a temperature between about 1600° and about 1900° F., maintaining the linear velocity of the mixture in said coil sufficient to prevent substantial combustion of the hydrocarbon therein, then passing the 20 heated mixture into an enlarged reaction zone at a somewhat reduced high linear velocity in the absence of a substantial amount of free hydrogen separately passed into said zone, partially combusting said mixture in said reaction zone at a temperature between about 2000° and about 3000° F., the average residence time of the mole- 25

cules undergoing reaction at said last mentioned temperature being less than about 0.01 second whereby substantial quantities of acetylene are produced, immediately quenching the reaction mixture, and separating acetylene therefrom.
